[57] CLAIM

The ornamental design for a reaction vessel for combining chemicals, as shown and described.

DESCRIPTION

FIG. 1 is a perspective view of the reaction vessel for combining chemicals showing my new design;

FIG. 2 is a top view of the reaction vessel for combining chemicals shown in FIG. 1;

FIG. 3 is a bottom view of the reaction vessel for combining chemicals shown in FIG. 1;

FIG. 4 is a front view of the reaction vessel for combining chemicals shown in FIG. 1, and further is a rear view of the reaction vessel for combining chemicals shown in FIG. 1; and,

FIG. 5 is a right side view of the reaction vessel for combining chemicals shown in FIG. 1, and further is a left side view of the reaction vessel for combining chemicals shown in FIG. 1.
